MOTOR FOR TOYS

Philipp Ullmann, Northampton, England

Application August 6, 1947, Serial No. 766,569
In Great Britain April 16, 1946Section 1, Public Law 690, August 8, 1946
Patent expires April 16, 1966

4 Claims. (Cl. 185—37)

1

This invention relates to toys, such as wheeled toys, clockwork, mechanical toys, and the like in which a frame or chassis is employed in which spindles, axles, or shafts are rotatably positioned. At present it is usual to form bearing holes in the side plates of the frame or chassis and to thread the spindles, axles, or shafts through the holes which in many cases necessitates fixing a gear or other wheel or member to the shaft or spindle between the side plates. This is fairly difficult in assembling, costly and requires skill, and the object of the present invention is to overcome this difficulty and thus reduce cost.

According to this invention, the frame or side plates for receiving the spindles, axles or shafts are suitably shaped and formed with slots leading from an edge or edges of each plate to the position the spindle, axle or shaft is to occupy, and a member or members suitably shaped is provided which can be positioned on the frame or side plates to close the openings to the slots and retain the spindles, axles, or shafts in the slots.

The invention will be clearly understood from the following description aided by the accompanying drawings, in which:

Figure 1 is a side view of a chassis of a toy clockwork vehicle showing one example of carrying the invention into effect. Figure 2 is a plan of same. Figure 3 is a perspective view of the top cover, and Figure 4 a perspective view of a bottom frame.

The invention can be carried into effect in various ways as to detailed construction.

In the example shown on the accompanying drawings for a clockwork driven toy vehicle, the chassis is formed of a plate 1 of suitable shape in which is formed a well 2 or depression. On the plate 1 and coinciding with the side edges of the well 2 is formed or provided a box-like frame 3. Said frame 3 is rectangular in plan and the front wall 4 is formed with a slot 5 next to the plate 1. The upper edges of the side walls of the frame 3 are angled upwards as at 6 and then downwards as at 7 to the rearward of the frame 3 where the rear wall 8 is of wedge shape with two studs 8a on the surface 7a.

In the straight portions 7 of the side walls of the frame 3 are formed slots 9 leading from the edges to the positions to be occupied by the shaft 10 of the driving wheels 11, axles 12, 12a of the train of gears and the spindle 13 carrying the spring (not shown) of the clockwork mechanism.

A top member 14 consisting of a plate having a longitudinal aperture is provided also of rectangular shape in plan with upwardly directed side

flanges 15 and with the plate shaped to the shape of the top of the frame 3 so that when the top member 14 is positioned on the lower member frame 3 it will close the openings to the slots 9 in the side walls of the frame 3, whereby the shaft 10, axles 12, 12a and spindle 13 run in the bottom frame 3 only and are held down by the top member 14 thus allowing the complete wheels and axles to be easily positioned in place by just placing the shaft 10, axles 12, 12a and spindle 13 in the slots 9 and applying the top member 14.

The top member 14 is conveniently formed at its forward end with a projecting lug 16 which is engaged in the slot 5 in the front wall 4 and two holes 17 in the rear end which engage over the studs 8a which are buried over to hold the top member 14 securely to the frame 3.

The top member 14 is formed with projections 18 projecting suitable distances into the aperture for retaining the shaft 10, axles 12, 12a and spindle 13 and wheels of the clockwork mechanism in proper position against longitudinal movement, and a downwardly projecting lug 18a which, when the top member 14 is in place, projects partly across the curved slot 9 on one side plate of the frame 3.

14a is a hole to which the outer end of the usual coiled spring may be secured, the other end being secured to a bracket 19 on the spindle 13. The spindle 13 is of square cross section engageable by a detachable winding key 20.

The slots 9 for the axle 12 of the intermediate gear wheel 21 are curved and somewhat deeper than the other slots so that normally the axle 12 rests in the bottom of the slot with its pinion 22 in mesh with the toothed wheel 23 on the winding spindle 13 and with the gear wheel 21 out of mesh with the pinion 24 on the driving wheel spindle 10 so that when winding up, in clockwise direction, the axle 12 and gear wheel 21 are rotated without rotating the driving wheels 11. On releasing the winding key 20 to allow the spring to unwind, the toothed wheel 23 through the pinion 22 lifts the axle 12 for its gear wheel 21 to engage with and rotate the pinion 24, shaft 10 and driving wheels 11, the lug 18a holding the axle 12 in proper engagement with the toothed wheels as shown in dash and dot lines in Figure 1.

50 The shaft 10 carries a gear wheel 25 meshing with a pinion 26 on the axle 12a, which axle 12a carries an eccentric shaped balance weight 26a.

An aperture is formed in the bottom of the well 2 for the gear wheel 21.

55 The plate 1 and frame 3 can be constructed in

any suitable manner and are conveniently formed integrally by die-casting.

Various other forms and arrangements of clockwork mechanism may be employed.

What I claim as my invention is:

1. A toy comprising a frame having a pair of side plates with slots leading from an edge of each plate to receive rotating spindles, said frame having a front end wall with a slot therein and a pair of studs at the rear end, and a member positioned on the side plates to close the openings to the slots for retaining the spindles in the slots, said member having a lug projecting into the slot in the front end wall of the frame and holes corresponding to the studs to secure the frame and member together. 15

2. A toy according to claim 1, in which the frame and member together form a box-like casing.

3. A toy according to claim 1, in which the member has a stamped out aperture with pro-

jections on the inner edges of the aperture acting as abutments.

4. A toy according to claim 1, in which the frame and member are each U-shaped in cross-section.
